UNITED STATES PATENT OFFICE.

LEVI B. HOWE, OF NEW YORK, AND HENRY W. SHEPARD, OF BROOKLYN,
N. Y., ASSIGNEES TO THE METALLIC HEEL STIFFENING COMPANY, OF
NEW HAVEN, CONN.

COUNTER-SUPPORT FOR BOOTS AND SHOES.

SPECIFICATION forming part of Letters Patent No. 236,705, dated January 18, 1881.

Application filed June 16, 1880. (No model.)

To all whom it may concern:

Be it known that we, LEVI B. HOWE, of New York city, in the county and State of New York, and HENRY W. SHEPARD, of Brooklyn, in the county of Kings, in said State, have invented certain new and useful Improvements in Counter-Supports for Boots and Shoes, of which the following specification is a description.

10 This invention relates to an improvement particularly applicable to metal counter stays or supports, such as are described and claimed in Reissued Letters Patent No. 9,030, of January 6, 1880; and the invention consists in flanging or turning over the upper edge of a metal stay or support, so as to form a smooth, dull edge or surface that will not cut into or deface the counter or lining of a boot or shoe, nor irritate the heel of a person wearing the 20 same, and in corrugating the sides of the support, so as to give greater strength and permit the use of lighter metal.

In the accompanying drawings, Figure 1 is a perspective view, showing our improvements; 25 and Fig. 2 is a sectional view taken on plane of the line $x-x$, Fig. 1.

Similar letters of reference indicate corresponding parts in both figures.

A designates a metallic counter-support, 30 having its upper edges, B, flanged outwardly, turned down and pressed against the outer side of the support until it is flush therewith. In practice these edges B are formed by a pair of rollers with bearing-surfaces adapted to 35 flange the edge of the support outwardly and turn it down, as described; but any other suitable mechanism to accomplish this result may be used.

C C' designate a series of transverse and vertical corrugations in the sides of the support, which may be made in any suitable manner. By forming these corrugations so that part of them run in a transverse and part in a vertical direction they are all at right angles to the edge of the support, thereby increasing 45 the resisting force of the metal at the point of greatest strain.

In the metal counter stays or supports heretofore used the sharp upper edges of the support would not only injure the counter or lining, or both, but would very often seriously annoy the person wearing the boot or shoe. By this improvement a smooth, dull edge or surface is produced which will not cut the lining or counter nor irritate the heel of the 55 wearer.

In the supports intended for finer grades of shoes the edge may be turned over on the inner side of the support instead of the outer.

By corrugating the sides of the support 60 they are materially strengthened, and consequently very much lighter metal may be used, thereby effecting considerable saving in the cost of material.

What we claim as our invention, and desire 65 to secure by Letters Patent, is—

A metal counter-support having its upper edges turned over and its sides corrugated, substantially as specified.

LEVI B. HOWE.

HENRY W. SHEPARD.
